United States Patent Office.

GEORGE V. SHEFFIELD AND BYRON WHITCOMB, OF WORCESTER, MASSA
CHUSETTS.

Letters Patent No. 72,690, dated December 24, 1867.

IMPROVED BELT-FASTENING.

The Schedule referred to in these Letters Patent and making part of the same.

KNOW ALL MEN BY THESE PRESENTS:

That we, GEORGE V. SHEFFIELD and BYRON WHITCOMB, both of the city and county of Worcester, and Commonwealth of Massachusetts, have invented certain new and useful Improvements in Belt-Fastenings; and we do hereby declare that the following is a full, clear, and exact description of the same, reference being had to the accompanying drawings, forming a part of this specification, in which—

Figure 1 represents a perspective view of our improved fastening, one end of which is shown attached to the end of a belt, and

Figure 2 represents a longitudinal section through the end of the belt and fastening, the section being shown through two of the points of two hooks.

To enable those skilled in the art to which our invention belongs to make and use the same, we will proceed to describe it more in detail.

In the drawings, A represents the central metal part of the fastening, from which project the hooks α , the latter being formed from the same strip of metal as the parts A.

The operation is as follows: Strips of metal are cut out, of the proper size to form a fastening, then the ends α cut or slitted, the ends cut pointed and then bent into hook-form, one half of the hooks being forced out one way and the other half the other way, so as to leave a space, d, between their points to receive the end of belt B.

In applying the fastening to a belt, slight incisions may be made in the ends of the belt, or the points of the hooks α may be forced into the ends of the belt without such incisions.

We prefer to make one half of the shanks b of the hooks on each end a little shorter, so that the points will stand when inserted relatively as shown in fig. 2. By this arrangement the hooks are not so liable to tear out.

As one half of the hooks on each end of the fastening are applied to opposite sides of the end of the belt, the latter is well protected from injuries and from all liability of striking against the shipper or belt-guides when in use.

Our belt-fastening is simple, and not liable to get out of order, and can be made very quick and cheaply.

If preferred, the shanks b may be cut tapering, so as to leave a greater space between the hooks α , when they are forced into the ends of the belt.

Having described our belt-fastening, what we claim therein as new and of our invention, and desire to secure by Letters Patent, is—

1. A belt-fastening, constructed substantially as shown and described.
2. Making one half or a part of the shanks of the hooks α longer than the others, for the purposes stated.

GEORGE V. SHEFFIELD,
BYRON WHITCOMB.
